US0D1100947S

(12) **United States Design Patent** (10) **Patent No.:** **US D1,100,947 S**
Baskerville (45) **Date of Patent:** **** Nov. 4, 2025**

(54) **DISPLAY SCREEN OR PORTION THEREOF WITH GRAPHICAL USER INTERFACE FOR A GAME**

(71) Applicant: **IGT**, Las Vegas, NV (US)

(72) Inventor: **Paul Baskerville**, Las Vegas, NV (US)

(73) Assignee: **IGT**

(**) Term: **15 Years**

(21) Appl. No.: **29/953,721**

(22) Filed: **Jul. 23, 2024**

(56)

(57) **CLAIM**

The ornamental design for a display screen or portion thereof with graphical user interface for a game, as shown and described.

DESCRIPTION

The sole FIGURE is a front view of a display screen or portion thereof with graphical user interface for a game showing my new design.

The outermost dashed broken lines depict a display screen that forms no part of the claimed design. The remaining broken lines illustrate portions of the graphical user interface that form no part of the claimed design.

1 Claim, 1 Drawing Sheet
